UNITED STATES PATENT OFFICE.

AUGUST VOELKER, OF BEUEL, NEAR BONN, GERMANY.

METHOD OF PRODUCING HOLLOW QUARTZ BODIES.

1,107,336.

Specification of Letters Patent. Patented Aug. 13, 1914.

Application filed August 13, 1909. Serial No. 512,693.

To all whom it may concern:

Be it known that I, AUGUST VOELKER, a citizen of the Empire of Germany, residing at Beuel, near Bonn-on-the-Rhine, in the Empire of Germany, have invented a new and useful Method of Producing Hollow Quartz Bodies, of which the following is a specification.

All those acquainted with the nature of quartz know, that there is a wide difference between ordinary glass and quartz, which must be taken into consideration. In an electric furnace the raw quartz (arenaceous quartz, quartz-sand) can be turned into a semi-liquid hot state, but it can never be made to melt, but will at once volatilize the moment that the temperature is further increased beyond that point at which the quartz has become semi-liquid. However, in this state the material can also be worked. The working of the semi-liquid hot quartz may be effected either within or without the furnace. For working the semi-liquid quartz without the furnace it has been proposed to introduce compressed air by means of special tools into the tubular plastic body. However, the introduction of the special tools (of iron, carbon, or the like) is a most difficult operation which frequently results in failure, since the quartz in its semi-liquid state will rapidly congeal, more particularly the ends of such a body being worked will rapidly be chilled and harden. Also the working of the semi-liquid hot quartz within the furnace, say by the introduction of compressed air through a perforated tube etc., creates great difficulties and frequently presents still greater defects than the first named method, since the tube is easily blocked up, becomes fragile, or will firmly adhere to the tough and stubborn material.

My invention relates to a method of forming diversified bodies from semi-liquid hot quartz with the aid of molds, while easily overcoming the said difficulties, and the new method is very simple, safe and cheap. The new method is characterized by the application to the tubular semi-liquid hot body to be worked of a foreign body capable of being wholly or partially gasified by the extreme heat of the quartz (about 2200° centigrade), so that the most rapidly developed gases

under high pressure can quickly act upon the body of quartz for forming it by blowing and pressing against the inside of a mold. Owing to the nature of quartz it is necessary to perform the various operations most quickly so as to prevent the quartz from prematurely congealing, and this is a further feature of the new method. The said foreign body adapted to be wholly or partially gasified by the extreme heat of the quartz to be worked, can be of almost any description. For example it may be a cover, wrapper, envelop, box, etc., of a more or less combustible material, such as paper, paste-board, leather, etc., also of tinfoil, asbestos, etc., and filled with a liquid or body to be evaporated or gasified, such as water, ice, hydrocarbon, any of the oils, etc. Or the foreign body may be a salt falling to pieces in the heat, such as chlorid of sodium, ammonium-chlorid, etc. Or the liquid contained in the body may be bound in it, such as is the case with earth-fruits, for example carrots, turnips, potatoes, and the like.

I will now proceed to describe my invention with reference to the accompanying drawings, in which—

Figures 1 to 3 illustrate for example three stages of the method of forming a hollow quartz body.

Similar letters of reference refer to similar parts throughout the several views.

The mold to be employed in the new method may be of any known construction, which will have to depend upon the size of the mass of semi-liquid quartz to be worked and upon the size of the body into which the material is to be turned. A mold of metal or the like and consisting of the halves *a* and *b* hinged together on the right side is provided with projections *c* and *d*, which may wholly or nearly come in contact with one another on the said mold being closed. The halves *a* and *b* may each have a cavity *f* (either circular or oval or of any other shape) and several air-holes *r*. A tubular semi-liquid quartz body *e* (Fig. 1) of sufficient length produced in an electric furnace by means of a resistance core is withdrawn from the furnace by means of tongs, most rapidly freed on its exterior from the loosely adhering arenaceous quartz,

and quickly placed with its ends on the projections *c* of the lower mold half *a*, so that it floats above the cavity *f* (Fig. 1) of the latter, while its ends project a little from the projections *c*. A foreign body to be gasified, in this case a potato *i* is pushed into the middle of the central cavity *m* of the extremely hot body *e* by means of a stalk of straw *h* or a pointed rod of wood 10 or the like, whereupon the upper mold half *b* is at once turned downward and pressed strongly on the lower mold half *a*, so that the projections *c* and *d* will squeeze the ends of the body *e* for closing its central cavity 15 *m* (Fig. 2). At this moment the stalk of straw *h* or pointed rod of wood if not withdrawn will already have been burned and leave with its slight ash hardly a colored trace, while the potato *i* will be instantaneously gasified by the extreme heat of the plastic quartz body *e* and the gases will rapidly blow the hollow body *e* and press the quartz against the inside of the mold 20 (Fig. 3), the air contained in the latter 25 escaping to without through the holes *r r*.

It is of the highest importance to perform the various operations described above most rapidly so as to prevent the quartz from prematurely congealing and thus to 30 avoid failures as much as possible. In this manner a closed hollow body *o p* is formed from the semi-liquid quartz in the mold *a b*, which body can be taken out of the mold, after the latter has been opened. When so 35 preferred, an annular protrusion *n* may be formed on the hollow body by suitably recessing the mold, and may be taken off in any known manner, for example by means of saws or other tools or a sand-blasting apparatus, etc., when the body will be divided 40 into two shells or plates *o* and *p* of quartz.

It is evident, that the mold may be varied in its construction in accordance with the finished article to be produced. It may be 45 made in several pieces and the several pieces may be composed in any known manner. The mold halves *a* and *b* shown need not be hinged together; they may be secured in any known manner on parts guided in some 50 press and arranged to be nicely moved together for closing the mold. The projections *c* and *d* shown may be replaced by sharp edges similar to stamps and dies for cutting off the excess of the semi-liquid 55 quartz. The mold may be so constructed as to form several independent hollow bodies at a time.

I claim:

1. The herein described method of producing a hollow quartz body, which consists in withdrawing from a furnace a tubular semi-liquid quartz body, freeing its exterior from the loosely adhering arenaceous quartz, placing it with its ends on the edge 60 of a lower mold part, introducing into its

cavity by means of a burnable tool a foreign body capable of being wholly or partially gasified by the extreme heat of the quartz, closing its cavity at both ends by squeezing the latter between the edges of the lower 70 and of an upper mold part, and retaining the mold parts closed while the developed gases blow the quartz body and press it against the inside of the mold, the various operations being performed rapidly so as to 75 prevent the quartz from prematurely congealing.

2. The herein described method of producing a hollow quartz body, which consists in withdrawing from a furnace a tubular 80 semi-liquid quartz body, freeing its exterior from the loosely adhering arenaceous quartz, placing it with its ends on the edge of a lower mold part, introducing into its cavity by means of a burnable tool a foreign body capable of being wholly or partially gasified by the extreme heat of the quartz, closing its cavity at both ends by squeezing the latter and cutting off the ends 85 of said tubular body between the edges of 90 the lower and an upper mold part, and retaining the mold parts closed while the developed gases blow the quartz body and press it against the inside of the mold, the various operations being performed rapidly 95 so as to prevent the quartz from prematurely congealing.

3. The herein described method of producing a hollow quartz body, which consists in withdrawing from a furnace a tubular semi-liquid quartz body, freeing it from the loosely adhering arenaceous quartz, placing it with its ends on the edge of a lower mold part, introducing into its cavity by means of a burnable tool a foreign body 100 capable of being wholly or partially gasified by the extreme heat of the quartz, closing its cavity at both ends by squeezing the latter between the edges of the lower and an upper mold part, and retaining the mold 105 parts closed while the developed gases blow the quartz body and press it against the inside of the mold, the various operations described so far being performed rapidly so as to prevent the quartz from prematurely congealing, and removing from the cooled hollow body and protrusions formed between 110 the two edges of the mold.

4. The herein described method of producing a hollow quartz body, which consists in 115 withdrawing from a furnace a tubular semi-liquid quartz body, freeing its exterior from the loosely adhering quartz, placing it with its ends on the edge of a lower mold part, introducing into its cavity by means of a 120 burnable tool a foreign body capable of being wholly or partially gasified by the extreme heat of the quartz, closing its cavity at both ends by squeezing the latter between 125 the edges of the lower and an upper mold 130

part, retaining the mold parts closed while the developed gases blow the quartz body and press it against the inside of the mold, the various operations described so far being performed rapidly so as to prevent the quartz from prematurely congealing, and dividing the cooled hollow body into two

parts in a line corresponding to the line of division between the two parts of the closed mold.

AUGUST VOELKER.
